AMOS FREDERICK DIXON, OF NEWARK, NEW JERSEY, ASSIGNOR, BY MESNE ASSIGNMENTS, TO WESTERN ELECTRIC COMPANY, INCORPORATED, A CORPORATION OF NEW YORK.

SELECTING SYSTEM.

1,262,654.

Specification of Letters Patent. Patented Apr. 16, 1918.

Application filed September 30, 1915. Serial No. 53,494.

To all whom it may concern:

Be it known that I, AMOS FREDERICK DIXON, a citizen of the United States, residing at Newark, in the county of Essex and 5 State of New Jersey, have invented certain new and useful Improvements in Selecting Systems, of which the following is a full, clear, concise, and exact description.

This invention relates to selecting systems 10 and its principal object is to provide an improved system for producing, or adapted to be operated upon by, sequential selective current impulses unseparated by no-current intervals.

15 Such a system is particularly adapted for use in printing telegraph communication over transmission lines subject to inductive disturbances which are apt to interfere with the passage of signaling current impulses. 20 Under such conditions the most accurate operation can be obtained by reversing the polarity of adjacent impulses and having the impulses run into each other without breaks or no-current intervals.

25 In accordance with its general characteristics, the invention, in its preferred embodiment, contemplates a current distributor co-operating with a current controller to produce a succession of alternating current impulses, the controller being also adapted to 30 affect the operation of the distributor to selectively modify the impulses so produced, to control the operation of distant and, if desired, also local selecting apparatus. The 35 distributor may also be variably affected by impulses of different characteristics arriving over a transmission line, whereby the selecting apparatus co-operating therewith may be selectively operated. In the preferred embodiment of the invention, the distribution 40 of impulses, either in transmitting or receiving, is not accomplished by the use of sequentially acting relays or by rotating commutators or brushes.

45 The above and other objects of the invention will be fully set forth in the following description and claims, and will be more readily understood by reference to the accompanying drawing wherein the preferred 50 embodiment is shown diagrammatically.

The sequential formation and distribution of the signal current impulses is controlled by an electromechanical apparatus, commonly called a distributor, which effects the

successive opening and closing of a plurality of switches. When the apparatus is adapted for forming and transmitting selective current impulses and distributing the effects of such impulses locally and also for distributing the effect of impulses received 60 from a distant transmitting station, the switches are arranged in two groups or sets, one set controlling the formation of impulses and the other set controlling the distribution of impulse effects. 65

The impulse-controlling or transmitting switches, when a five-impulse selecting code is used, comprise a plurality of switches 1, 2, 3, 4 and 5, and the impulse-controlled or receiving switches comprise an equal number of switches 11, 12, 13, 14 and 15. These switches are arranged in pairs and are operated by an actuator 16 through the agency of a plurality of pairs of insulated pins 21, 22, 23, 24 and 25. The actuator 16 is adapted to be reciprocated by an operating or stepping electromagnet 26 through the agency of a spring-tensioned armature 27. 70 75

In order that the repeated energization and deenergization of electromagnet 26 may 80 cause the successive operation of the pairs of switches, the switches may be arranged in slightly different planes. Thus, the switches 1 and 11 will be located above switches 2 and 12, which in turn are above switches 3 and 13, and so on in stair-like formation. If desired, however, the switches may be arranged in one plane and the pins 21 to 25 located on actuator 16 in different planes, pins 21 being in the lowest plane and pins 25 90 in the highest. The movement of actuator 16 is directed by a movement-controlling mechanism comprising a pivoted and spring-tensioned stepped member 28 on whose steps a projection 29 of actuator 16 is adapted to 95 rest. The energization of electromagnet 26 moving actuator 16 to the left, causes projection 29 to drop down one step on member 28, and the subsequent deenergization thereof allows the spring of armature 27 to 100 move actuator 16 to the right, closing one of the pairs of switches and carrying with it the member 28. A pivoted spring-tensioned holding pawl 30 co-operates with the steps of member 28 to hold that member in each 105 new position into which it is moved by the successive deenergizations of electromagnet 26. At the end of a cycle of operations, a

restoring mechanism, operated by a restoring electromagnet 36, causes the return of the entire mechanism to normal position. This mechanism comprises a spring-tensioned 5 armature 37 pivotally connected to a restoring lever 38, lever 38 being provided with a pair of pins 39 and 40 for engaging and elevating actuator 16 and pawl 30 respectively.

The character of the impulses formed is 10 selectively determined by a current impulse controller of a well-known type, comprising a plurality of switches 41, 42, 43, 44 and 45. These switches are each preferably formed of a movable contact located between and 15 adapted to engage either of two fixed contacts. In the embodiment shown in the drawing, the left-hand fixed contacts of all of the switches 41 to 45 are connected to the winding of an impulse control relay 46, and 20 the right-hand fixed contacts are connected to a stepping relay 47 and an armature 48 of relay 46. Armature 48 coöperates with a front contact connected to a grounded source of energy 49. The movable contacts of 25 switches 41 to 45 inclusive are connected to one of the members of switches 1 to 5, respectively.

Normally, the movable contacts of switches 41 to 45 rest against their respective right-hand fixed contacts, but they are adapted by any of the well-known selecting means to be selectively transferred to the left-hand fixed contacts. This means may consist of the usual manually actuated apparatus 30 wherein the controlling keys are arranged in the form of an ordinary typewriter keyboard, or it may consist of automatic apparatus controlled by a perforated paper tape or the like. Preferably the manual or automatic apparatus, simultaneously with the 35 selective transfer of switches 41 to 45, transfers a pair of movable contacts 56 and 57 of a pair of operating switches from their co-operating contacts 58 and 59, respectively, to contacts 60 and 61. Contact 56 is connected through a winding 62 of a transmitting relay 63 to a grounded source of energy 64, and contact 57 is connected to source 64 through a winding 65 of relay 63. Contacts 40 60 and 61 are connected to one of the members of certain of the transmitting switches 1 to 5; contact 60 to switches 1, 3 and 5, and contact 61 to switches 2 and 4. Contact 59 is grounded while contact 58 is not connected 45 to any part of the system.

One member of each of the receiving switches 11 to 15 inclusive is connected through a corresponding selecting mechanism 71, 72, 73, 74 and 75 of any desired 50 form of selecting apparatus to a grounded source of energy 76. One form of such apparatus is disclosed in Patent No. 1,103,133, issued July 14, 1914.

The transmission line L, to which the 55 pulses may be imparted to operate a select-

ing apparatus, similar perhaps to that disclosed in the above patent, is connected to a pair of blades 77 and 78 of a line and control switch. Preferably, this switch is also provided with two other blades 79 and 80, 70 although any other arrangement may be readily employed, and, to give uniformity, each blade is capable of taking three positions. In the drawings all of the blades are shown in the position for transmitting impulses to line. The second position is the receiving position, and the third or lowest position is the normal or Morse setup, as will be hereinafter explained.

A contact 85, coöperating with blade 77 80 in the first position of the line and control switch, is connected to an armature 86 of relay 63, which armature coöperates with contacts connected to the positive and negative terminals of a suitable line battery or 85 other source of current. Contacts 87 and 88 are connected through the windings of a polarized receiving relay 89 to ground. A contact 90, coöperating with blade 78 in its lowermost position, is connected through an 90 ordinary telegraph key 95 and sounder 97 to a grounded source of energy 98. A contact 99, coöperating with blade 80, is connected to an armature 100 of stepping relay 47, one terminal of electromagnet 26, the 95 other terminal of which is connected to a grounded source of energy 101, and to a front contact coöperating with an armature 102 of a restoring relay 103. Blade 79 coöperates with contacts 104 and 105, and is connected to one element of a local switch 106, closed at the same time as switch 15, the other element of which is connected through relay 103 to a grounded source of energy 107. Contact 104 is connected to contact 99, while 105 contact 105 is connected to one terminal of a winding 110 of a control relay 111, a contact 112 coöperating with armature 113 of relay 89 and a contact 114 coöperating with an armature 115 of relay 111. Blade 80 is 110 connected to armature 115. A contact 120, coöperating with armature 113, is connected to one terminal of a winding 121 of relay 111 and one element of a normally open switch 122, the other element of this switch 115 being connected to a contact 123 coöperating with armature 115 of relay 111. Switch 122 is normally open but is closed when actuator 16 is withdrawn on its first step, for a purpose to be hereinafter described.

The other terminals of the windings 110 and 121 of control relay 111 are respectively connected through one of a pair of selecting relays 125 and 126 to grounded sources of energy 127 and 128. Winding 125 110 is also connected to a front contact coöperating with armature 130 of relay 125, and winding 121 is also connected to a front contact coöperating with armature 131 of relay 126. Armature 131 is connected to 130

one element of switches 11, 13 and 15, and armature 130 is connected to a corresponding element of switches 12 and 14. An armature 135 of relay 125 coöperates with 5 a grounded back contact and is connected through a sixth-impulse relay 136 to armature 137 of relay 103 and armature 138 of relay 47. Relay 136 has a grounded armature 140 coöperating with a front contact 10 connected to one element of switches 2 and 4 and contact 61.

Impulse control relays 46, 125 and 126 are made slow-acting, preferably by placing in series with their windings suitable inductive resistances, as shown, to give the 15 desired amount of lag in operation. These relays should not operate in the time of the flow of a non-selecting impulse but will operate on a flow of current for the length 20 of time of a selecting impulse. Relays 63, 89 and 111 are of the ordinary polarized type wherein the armature, when moved against one of its coöperating contacts by current of a certain polarity, remains in 25 that position until current of the opposite polarity becomes active.

The operation of the system, when acting as a combined current impulse transmitter and local selector, is as follows, all 30 of the blades of the line and control switch being in the first position as shown: Assuming that the desired selection requires lengthened second, third and fifth impulses, the keyboard or automatic control apparatus 35 transfers contacts 42, 43 and 45 from the right-hand to the left-hand fixed contacts, and contacts 56 and 57 from contacts 58 and 59 to contacts 60 and 61 respectively. The normally closed circuit from source 64 40 through winding 65 of relay 63 and contacts 57 and 59, which insures that negative current is normally flowing over line L and through the receiving relay 89, when the line and control switch is in the first or 45 upper position, is thereupon interrupted and a circuit for winding 62 closed. This circuit extends from source 64 through contacts 56 and 60, normally closed switch 1, switch 41 and stepping relay 47 to ground. 50 Winding 62 and relay 47 are operatively energized. Winding 62 moves armature 86 against its left-hand coöperating contact, and positive current for the first impulse of the selective combination flows over line L 55 to a distant selecting station, which is preferably identical with that hereinbefore described, and through the local receiving relay 89. Relay 47 attracts armature 100 and a circuit is closed from source 101 through 60 electromagnet 26, which pulls up its armature 27 moving actuator 16 to the left. The pulling up of armature 138 performs no function at this time. This movement of actuator 16 opens switches 1 and 11 and 65 closes switch 122. It also causes the projec-

tion 29 to drop down on to the next lower step of member 28. The opening of switch 1 interrupts the previously traced circuit through relay 47, which releases its armature 100 to open the previously traced circuit through electromagnet 26, and the spring returns armature 27 and moves actuator 16 to the right. Projection 29 is now, however, on the next forward and lower step, and member 28 is rotated to the 70 right, allowing pawl 30 to drop down one step.

During these later operations the positive current flowing through the receiving relay 89 moves armature 113 from contact 112 80 to contact 120. The normally closed circuit from source 127 through relay 125, winding 110, contact 112 and armature 113 is thereupon opened, and a circuit is completed from source 128 through relay 126, winding 121 of relay 111, contact 120 and armature 113 to ground. The opening of the circuit through relay 125 releases armatures 130 and 135. Winding 121 of relay 111 85 now shifts armature 115 to contact 114, but 90 this transfer performs no function at this time.

The retraction of actuator 16 to the right, as hereinbefore mentioned, closes switches 2 and 12, and a circuit is completed from 95 source 64 through winding 65 of relay 63, contacts 57 and 61, switch 2 and, because switch 42 is transferred, through relay 46 to ground. Winding 65 moves armature 86 to again transmit negative current for the 100 second impulse to the line and to relay 89. Relay 89 moves armature 113 again into engagement with contact 112, and the circuit through winding 121 and relay 126 is interrupted. This circuit, moreover, has not 105 been completed long enough for the retarded relay 126 to become sufficiently energized to attract its armature. Through the transfer of armature 113, winding 110 and relay 125 receive current and armature 115 110 is moved to reengage contact 123.

The previously traced circuit through winding 65 and relay 46 causes relay 46 to attract its armature 48 and a circuit is completed from source 49 through armature 48 115 and relay 47 to ground. The energization of relay 47 causes the operation of electromagnet 26 and switches 2 and 12 are opened. The opening of switch 2 causes the deenergization of relay 46 and the consequent deenergization of relay 47 and electromagnet 26. Thereupon actuator 16 moves again to the right, this time in such a position that pins 23 close switches 3 and 13.

The delay in the preceding energization 125 and deenergization of relay 47, consequent upon the lag of relay 46, allows current to flow from source 127 through relay 125, winding 110, contact 112 and armature 113 to ground for a sufficient length of time to 130

- allow the operative energization of relay 125, and armatures 130 and 135 are attracted. Armature 130 completes a circuit from source 76 through mechanism 72, 5 switch 12, armature 130 and its front contact, winding 110, contact 112 and armature 113 to ground, causing mechanism 72 to perform its part in the operation of the local selecting apparatus.
- 10 The previously mentioned second return movement of actuator 16 will cause the closing of switches 3 and 13 and reverse the condition of armature 86, and the third impulse (positive) is initiated. Also, since switch 15 43 is transferred, relay 46 and consequently relay 47 and electromagnet 26 are energized and then deenergized, as before. Actuator 16 being moved down another step closes switches 4 and 14. This third impulse also, 20 because of relay 46, is sufficiently long to energize relay 126 after armature 113 has been moved by the impulse reversal into engagement with contact 120. Relay 126 pulling up its armature 131 completes a circuit 25 for mechanism 73 from source 76, through switch 13, armature 131 and its front contact, winding 121, contact 120 and armature 113 to ground, before this switch was opened as above noted.
- 30 The closing of switches 4 and 14, respectively cause relay 63 to start the fourth impulse (negative) and place mechanism 74 in a circuit including armature 130. This circuit, however, is not completed since the 35 fourth impulse, switch 44 not having been transferred, is not of sufficient duration to allow the operation of relay 125. The fourth impulse being negative and of short duration magnet 26 is energized only momentarily, 40 moving actuator 16 first to the left and then releasing it and permitting it to move to the right in the next lower plane, thereby closing switches 5 and 15. When last or fifth impulse (positive) is initiated switch 5 is 45 closed, completing a circuit for winding 62 of relay 63, causes armature 86 to be moved to the left. At the same time switch 15 is closed, switch 106 is also closed, and a circuit is partly prepared from source 107, 50 through restoring relay 103, switch 106, blade 79 and contact 104 to armature 100 of stepping relay 47, which circuit is completed when relay 47 is energized by the closing of switch 5. The fifth impulse being positive 55 and switch 45 having been moved to the left by the keyboard mechanism, relay 47 is energized by the closing of contact 48 of magnet 46 which is a slow magnet. This delays the energization of magnet 46 and consequently the energization of magnet 26 and 60 the movement of actuator 16 to the left. Consequently the opening of switch 15 is delayed until after the positive impulse is sent to line and transmitted through switch 65 arm 78 the relay 89 has moved armature 113 to the left to contact 120, whereupon a circuit is closed from ground, armature 113, contact 120, winding 121, slow relay 126. This relay 126 pulls up its armature 131 thereby completing a circuit for the selector 70 mechanism 75 from ground, armature 113, contact 120, winding 121, armature 131, switch 15, selector mechanism 75, to grounded source of energy 76. As soon as magnet 26 is energized, actuator 16 opens 75 switch 15 and interrupts the above mentioned circuit. The attraction of armature 102 of restoring relay 103 retains the electromagnet 26 in an energized condition irrespective of the condition of relay 47 which, 80 in previously pulling up its armatures when switch 5 was closed, has caused electromagnet 26 to be energized, and completes a circuit for a grounded source of energy 141, through restoring electromagnet 36. Electromagnet 36 attracts its armature 37, and through lever 38 and pins 39 and 40 actuator 16 and pawl 30 are elevated. Member 28 thereupon rotates to the left, and when electromagnets 26 and 36 are again deenergized, 85 projection 29 rests upon the top step of member 28, and pins 21 close switches 1 and 11 as at the beginning. Armature 137, in pulling up, closes a holding circuit for relay 103 from source 107, through armature 90 138 of stepping relay 47, and also completes a circuit from source 107 through the sixth impulse relay 136 and armature 135 and its back contact, relay 125 being deenergized at this time. This last circuit, however, because of the short-circuit to ground through armature 138, does not cause the operative 95 energization of relay 136 until stepping relay 47 is deenergized. This short-circuiting of relay 136 is necessary in order that the 100 duration of the last or fifth selecting impulse may be determined by the condition of switch 45.
- 105 Relay 47 becoming deenergized by the opening of switch 5, relay 136 operates, and a circuit is completed from source 64 through winding 65, contacts 57 and 61 and armature 140, causing relay 63 to reverse the condition of its armature and connect negative current to line L and relay 89. Relay 89 thereupon 110 reverses the condition of its armature 113 and current flows from source 127 through relay 125 and winding 110. When current has been flowing through relay 125 for a sufficient length of time to cause it to attract 115 its armatures, the ground at armature 135 is removed from the previously traced circuit through relays 103 and 136, and these relays return to normal, allowing electromagnets 26 and 36 to also return to normal, and the 120 entire system is in a condition to begin a new cycle of operations.
- 125 If desired, relay 136 may also control any of the well-known locking arrangements for retaining switches 41 to 45 in selected 125 130

position until the entire combination of impulses has been formed.

When the apparatus disclosed is to be used as a distributor of the effects of line current impulses arriving from a distant station over transmission line L, the blades of the line and control switch are placed in the second position. The first impulse of a selective combination being positive 5 reverses the condition of receiving relay 89, whose armature 113 is moved into engagement with contact 120. A circuit is then completed from grounded source 128 through relay 126, winding 121, contact 15 120 and armature 113 to ground, which results in armature 115 moving into engagement with contact 114. If this impulse is a non-selecting impulse, the polarity of the current is reversed before relay 126 has time 20 to attract its armature. It will be noted that the first impulse did not effect the energization of stepping electromagnet 26 and that switches 1, 2 and 122 are still in normal condition. The reversal of the line 25 current on the second impulse causes receiving relay 89 to move its armature 113 into reengagement with contact 112, and a circuit is completed from source 127 through relay 125 and winding 110.

From the time of the engagement of armature 113 and contact 112 until the disengagement of armature 115 and contact 114, a circuit is also completed from source 101, through stepping electromagnet 26, 30 contact 99, blade 80, armature 115, contacts 114 and 112, and armature 113 to ground. This circuit is maintained only a sufficient length of time to cause the energization of electromagnet 26, but this magnet is again 35 deenergized as soon as armature 115 leaves contact 114 and switches 2 and 12 are closed. Switch 122 is also closed from the time of the first withdrawal of actuator 16. If the second impulse is a selecting impulse, negative current is maintained upon the line 40 long enough to cause relay 125 to attract its armatures, whereupon a circuit is completed from source 127, through relay 125, front contact and armature 130, switch 12 and mechanism 72 to ground, whereupon 45 mechanism 72 performs its function in the operation of the selecting apparatus.

The third impulse reverses the conditions of receiving relay 89 and control relay 111, 50 and electromagnet 26 is momentarily energized, by current flowing from source 101 through contact 99, blade 80, armature 115, contact 123, switch 122, contact 120 and armature 113 to ground, to cause actuator 16 to take an additional step. These 55 operations continue for each impulse, whenever an impulse is of long duration, the corresponding selecting mechanisms 73 to 75 being operated. The fifth impulse, in addition to closing switch 15, closes switch 106,

and a circuit is partially prepared from source 107, restoring relay 103, switch 106, blade 79, and contact 105 to contact 112. Ground is placed upon this circuit when armature 113 engages contact 112 upon the 70 arrival of the sixth or negative line impulse. Relay 103 thereupon attracts its armatures, and through the energization of electromagnets 26 and 36, actuator 16 and member 28 are returned to normal as hereinbefore described, switches 1 and 11 are closed, and switch 122 is opened.

It will be noted from the foregoing description that the operation of the distributor is slightly different when it is acting to produce line current impulses and effect local selections than when it is being controlled by impulses received from the transmission line. In the latter case, the first selecting impulse (positive) exercises no effect upon the stepping electromagnet 26 because switch 122 is open. For each impulse after the first, however, the electromagnet 26 is energized and deenergized to open the switches 12 to 15 corresponding to the next preceding impulse and to close the switches corresponding to the impulse received. In other words all of the impulses after the first must close the corresponding switches 12 to 15 before the 95 corresponding mechanisms 72 to 75 may be operated. This method of operation, when the system is acting simply as a receiver, is necessary since a long negative impulse always follows the fifth selecting 100 impulse. This negative impulse, however, must have no effect upon the distributor, which result is obtained by the provision of switch 122, which opens what otherwise might be a normal circuit over the path 105 previously traced through armatures 113 and 115 and electromagnet 26, when the actuator 16 has returned to normal on the fifth selecting impulse as previously described. Switch 122 therefore prevents the 110 actuation of the distributor upon the sixth or first impulses, although when closed, because of the action of the second impulse, it provides an energizing circuit for electromagnet 26 when armature 113 engages 115 contact 120 on the third and fifth impulses. On the second and fourth impulses, electromagnet 26 is energized by the momentary current passing through armatures 113 and 115 and contacts 112 and 114, as hereinbefore described.

In the normal condition of the line, all of the blades of the line and control switch are preferably in their third or lowermost position so that the transmission line is associated with key 95 and sounder 97 for the usual Morse operation.

It will be readily apparent from the foregoing description that in case a station is equipped merely for the purpose of receiv-

ing signal current impulses from a distant station, all of the apparatus, which is adapted for use merely in the transmission of selective current impulses, may be dispensed with, and that if the station is to be equipped merely as a transmitting station, the apparatus adapted merely for selective operation upon the receipt of impulses from a distant station, or even the selecting apparatus controlled by mechanisms 71 to 75 inclusive, may be eliminated.

The invention claimed is:

1. A selecting system comprising a current controller, a current distributor coöperating therewith to form a succession of current impulses, and means under the control of said controller for retarding the operation of said distributor to selectively modify impulses so produced.
2. A selecting system comprising a current controller, a step-by-step current distributor coöperating therewith to form a succession of current impulses, and means under the control of said controller for retarding any of the steps of said distributor to selectively modify the impulses produced.
3. A selecting system comprising a current controller, a step-by-step electromechanical distributor coöperating therewith to produce a succession of current impulses for transmission and to operate said distributor, and a relay energized through the agency of said controller and retarding the operation of said distributor to selectively produce lengthened impulses.
4. A selecting system comprising a selecting apparatus, a plurality of sequentially acting switches divided into two groups co-operating therewith, means responsive to current impulses for effecting the sequential operation of said switches, and selectively operable means associated with each group of switches and affected only by impulses of prolonged duration whereby said apparatus is variably operated.
5. A selecting system comprising a selecting apparatus, a plurality of sequentially acting switches divided into groups co-operating therewith, means responsive to current impulses for effecting the sequential operation of said switches, and a slow acting relay associated with each group of switches and selectively energized by impulses of comparatively long duration, whereby said apparatus is variably operated.
6. A selecting system comprising a current controller, a selecting apparatus, a reciprocating current distributor coöperating with said controller and said apparatus to produce a succession of current impulses and effect a desired selection, means made operative by said controller to produce current impulses with certain characteristics, and means operable only on such impulses and coöperating with said distributor to control the operation of said apparatus.
7. A selecting system operable upon various combinations of sequential current impulses comprising a plurality of selecting mechanisms, a distributor, an electromagnet for operating said distributor to bring the impulses into operative relation to said mechanism, and means for rendering said electromagnet unresponsive to the first impulse.
8. A selecting system operable upon various combinations of sequential step-by-step current impulses comprising a current distributor, an electromagnet therefor, a relay characteristically responsive to current impulses, a second relay responsive to the first said relay, and independent circuits for energizing said electromagnet, each controlled by both of said relays.

In witness whereof, I hereunto subscribe my name this 28th day of September, A. D. 1915.

AMOS FREDERICK DIXON.
